UNITED STATES PATENT OFFICE.

SAMUEL L. MOYER, OF CINCINNATI, OHIO, ASSIGNOR TO THE LUNKENHEIMER COMPANY, OF SAME PLACE.

LOW-WATER ALARM FOR STEAM-BOILERS.

SPECIFICATION forming part of Letters Patent No. 656,203, dated August 21, 1900.

Application filed June 25, 1900. Serial No. 21,472. (No model.)

To all whom it may concern:

Be it known that I, SAMUEL L. MOYER, a citizen of the United States, residing at Cincinnati, in the county of Hamilton and State 5 of Ohio, have invented certain new and useful Improvements in Low-Water Alarms for Boilers, of which the following is a full, clear, and exact description, reference being had to the accompanying drawings, forming part of 10 this specification.

My invention relates to that class of low-water alarms for boilers which employ a tube extending into the boiler with its lower open end extending down into the water of the 15 boiler to the low-water level and which has at its upper end a whistle communicating with said tube and so controlled that when the water reaches the low-water level the lower end of the tube is unsealed and steam passes 20 up through the same and sounds the whistle, thus indicating that the water in the boiler has reached the low-water level and needs to be resupplied to the boiler; and it has for its 25 object the provision of simple and efficient means in the construction of a low-water alarm that will not only act automatically when the water in the boiler reaches the danger-point, but which can be tested at any time by an inspector to ascertain that the apparatus 30 is in working order, as required by the present laws of Ohio and Michigan, and perhaps of other States.

The novelty of my invention will be hereinafter more fully set forth, and specifically 35 pointed out in the claims.

In the accompanying drawings, Figure 1 is a central sectional side elevation of a low-water alarm embodying my invention in working position, a portion of the boiler being also 40 shown in section. Fig. 2 is a corresponding view of the upper part of the apparatus looking from the left of Fig. 1.

The same letters of reference are used to indicate identical parts in both figures.

45 A represents a vertical tube whose lower end is screwed into a tubular plug B and whose lower end is tapped through the crown-sheet of the boiler C. Upon the upper end of the tube A is screwed a valve-casing D, provided 50 with a diaphragm a, into the lower portion of which is screwed a second tube E, which

passes centrally down through the tube A, leaving an annular space b in the tube A, around the tube E, and thence down into the boiler, where its lower open end terminates at 55 the level of low water, (indicated by the dotted line c,) the normal water-level being indicated by the dotted line d. The diaphragm a forms three chambers e, f, and g within the valve-casing, and into the chamber f the 60 upper open end of the tube E enters. On opposite sides of the valve-casing are two horizontal exteriorly-threaded nipples h, upon which are screwed unions i, carrying and securing in place bonnets j, interiorly 65 threaded to receive and engage threaded valve-stems k, carrying on their inner ends valve-disks l, which engage seated openings m through the vertical walls of the diaphragm a. Upon the outer ends of the bonnets are 70 screwed tubular caps n, into which the outer ends of the valve-stems k project and are squared or flattened on their ends to receive and be engaged by a removable key F, by means of which the valves are opened and 75 closed as desired.

Upon the top of the valve-casing there is a tubular shell G, whose lower end is screwed into the top of the valve-casing and whose upper end is interiorly threaded to receive a 80 threaded plug o, provided with a central aperture which is flaring at its lower end. Within the shell G there is a diaphragm p, having a central aperture to form a seat for a fusible plug H, which is inserted from the under 85 side through the aperture in the plug o, which it snugly fits, and has its enlarged lower end bearing upon and covering the aperture in the diaphragm p. There is a chamber r around the diaphragm p opening into an 90 elbow extension I, Fig. 2, projecting from the shell G, and upon the upper open threaded end of said extension I is screwed the base of a whistle J of the usual or any suitable construction.

When the apparatus is in use, the valve which gives access from the annular space b of the tube A and the chamber e to the chamber g is closed and the opposite valve is open, giving access through the tube E and chamber f to the chamber g, and so long as the water in the boiler does not reach or extend 95 100

below the danger-level *c* the fusible plug *H* cuts off communication with the whistle, as will be readily understood; but the moment the water in the boiler descends sufficiently to 5 unseal the lower end of the tube *E* live steam passes up therethrough, through the chambers *f* and *g*, to the under side of the fusible plug *H*, whose lower end is almost instantly fused, permitting the steam to escape through the 10 elbow *I* to the whistle *J*, which is sounded to give the alarm, and the attendant at once is notified to look after his boiler-feeding apparatus or in other ways to resupply the boiler with water. Should an inspector at any time 15 desire to test the apparatus, he merely closes the valve between the chambers *f* *g* and opens the opposite valve, whereupon steam from the steam-space of the boiler passes at once through the annular space *b* and chambers *e* *g* 20 to the under side of the fusible plug, which is at once fused to permit steam to pass to the whistle, as before. Of course whenever a plug is fused it is removed and replaced by a new one by simply taking out the plug *o*, knocking 25 out the partially-fused plug *H*, reinserting a new one, and then returning the plug *o* to place, with the new fusible plug covering the aperture in the diaphragm *p*.

The apparatus above described and shown 30 applied to the crown-sheet of a boiler is equally applicable to a water-column upon the side or end of the boiler, where it will act in the same manner as above described.

One of the chief advantages of my construction, aside from its cheapness of construction and efficiency of action, lies in the fact that but one opening has to be tapped into the boiler through its crown-sheet, for both of the tubes *A* and *E* are contained 35 within that one opening.

Having thus fully described my invention, I claim—

1. In a low-water alarm, the combination of a tube communicating at its lower end with

the steam-space of a boiler, a second tube 45 within the first-mentioned tube whose lower end is submerged in the water of the boiler and extends to the low-water level thereof, a valve-casing upon said tubes provided with two valve-controlled openings one giving access from the first-mentioned tube and the other from the interior tube, a whistle carried by said valve-casing, and a fusible plug interposed between the whistle and the valve-casing, substantially as described. 50

2. In a low-water alarm, the combination of a tube communicating at its lower end with the steam-space of a boiler, a second tube within the first-mentioned tube whose lower end is submerged in the water of the boiler 60 and extends to the low-water level thereof, a valve-casing upon said tubes provided with two oppositely-set valves controlling openings the one from the first-mentioned tube and the other from the interior tube, a whistle 65 carried by said valve-casing, and a fusible plug interposed between the whistle and the valve-casing, substantially as described.

3. The herein-described low-water alarm composed of the tube *A* opening into the 70 steam-space of the boiler, the tube *E* within the tube *A* extending at its lower end to the low-water level of the boiler, the valve-casing *D* upon the upper ends of said tubes provided with the diaphragm *a* forming the chambers 75 *e* *f* *g*, the oppositely-set valves *l* with operating mechanism therefor controlling openings between the chambers *e* and *g* and *f* and *g* respectively, (the tube *A* opening into the chamber *e* and the tube *E* opening into the 80 chamber *f*) the whistle *J* carried by the valve-casing *D*, and a fusible plug covering an aperture between the chamber *g* and said whistle, substantially as described.

SAMUEL L. MOYER.
